UNITED STATES PATENT OFFICE.

WALTER O. McDANIEL, OF INDIANAPOLIS, INDIANA, ASSIGNOR TO THE H-K TOY & NOVELTY CO., OF INDIANAPOLIS, INDIANA, A CORPORATION OF INDIANA.

TOY MACHINE-GUN.

1,328,929.

Specification of Letters Patent. Patented Jan. 27, 1920.

Application filed June 12, 1918. Serial No. 239,617.

To all whom it may concern:

Be it known that I, WALTER O. McDANIEL, a citizen of the United States, residing at Indianapolis, in the county of Marion and 5 State of Indiana, have invented a new and useful Toy Machine-Gun, of which the following is a specification, reference being had to the accompanying drawings and to the letters and figures of reference marked 10 thereon.

This invention relates to a cannon or gun that is designed to be mechanically operated and not be a source of danger due to fire or explosions of combustibles, the invention 15 having reference more particularly to a machine gun that is adapted to be used as an instructive and amusing toy.

An object of the invention is to provide a machine gun which shall be of simple and 20 inexpensive construction and simple in operation, yet be durable and economical in use.

Another object is to provide a machine gun which shall be so constructed as to be able to expel simple and inexpensive projectiles with realistic effect and without 25 danger to the operator, or to others when not carelessly operated.

A further object is to provide a machine gun which may be constructed principally 30 of wood and rapidly by machinery, and which shall be strong and free from delicate parts liable to become damaged or deranged.

With the above-mentioned and other objects in view, the invention consists in a 35 mechanically operated machine gun adapted to successively expel a large number of projectiles; and the invention consists also further in the novel parts, and in the combinations and arrangements of parts, as hereinafter particularly described and further 40 defined in the accompanying claims.

Referring to the drawings,—Figure 1 is a side elevation of the novel machine gun or 45 cannon; Fig. 2 is a rear elevation of the novel machine gun; Fig. 3 is a top plan of the machine gun; Fig. 4 is a fragmentary view of the under side of the breech-end portion of the gun barrel; Fig. 5 is a section on the line V—V in Fig. 4; Fig. 6 is a fragmentary section approximately on the line VI—VI in Fig. 1; Fig. 7 is a fragmentary side view of the breech-end portion of the gun barrel; Fig. 8 is a fragmentary vertical central sectional view longitudinally of the 55 gun barrel; Fig. 9 is a fragmentary horizon-

tal central section longitudinally and centrally of the gun barrel; Fig. 10 is a vertical central section of the gun stock having operating mechanism connected therewith; Fig. 11 is a plan of the operating crank 60 shaft of the machine; Fig. 12 is a top plan of the gun stock; Fig. 13 is an end elevation of the gun stock; and, Fig. 14 is a fragmentary detail of the magazine of the machine gun. 65

Similar reference characters on the different figures of the drawings indicate corresponding elements or features of construction herein referred to in detail.

As preferably constructed the novel machine gun comprises a wooden base 1 provided on its top with a vertical center-pin 2, the top of the base having a circular ball race or groove 3 therein concentric to the center-pin. A suitable number of bearing 70 balls 4, 4', are placed in the ball race and may be cheaply composed of burned clay. A wooden platform 5 is arranged upon the bearing balls and has trunnion-blocks 6 and 7 thereon and also a center-hole 8 arranged 75 between the trunnion-blocks and receiving the center-pin 2, the latter being provided with a head 9 arranged upon the platform 5. The trunnion-blocks support a trunnion or pinion 10 between them in horizontal arrangement. The trunnion or pinion has a head 11 engaging one of the trunnion-blocks and a wing-nut 12 engaging the opposite one of the trunnion-blocks whereby the trunnion-blocks may be slightly drawn together 80 to securely clamp a gun stock 13 which has a pivot hole 14 therein receiving the pivotal device 10, a portion of the gun stock being arranged between the trunnion-blocks. 85

The gun stock 13 has two projecting wings 90 or side plates 15 and 16 integral thereon at a suitable distance apart to provide a chamber or lock-case. The upper portion of the gun stock has two upward extending side bars 17 and 18 thereon adapted to directly 95 support the main portion of the gun barrel. The wings 15 and 16 have rearwardly extending journal members 19 and 20 thereon to rotatably support a magazine cylinder. The gun stock is composed of wood and preferably has metallic side plates 21 and 22 thereon. The journal members 19 and 20 have upper and lower rounded portions 23 formed as segments of a circle so that the magazine cylinder 24 which is provided may 100 105 110

be rotatably guided thereon, the cylinder preferably having a central bushing or journal box 25 composed of metal so as to afford a smooth bearing. The cylinder has 5 a suitable number of openings to receive projectiles and preferably are formed as grooves or pockets 26, 26' extending cross-wise in the periphery of the cylinder. A spring-casing is provided which comprises 10 a front plate 27 arranged against the ends of the members 19 and 20 and a circular rim portion 28 extending from the plate to the cylinder, the casing being secured in place by means of nails 29 driven through the 15 plate 27 and into the members 19 and 20. The front plate of the casing has an aperture 30 therein. A spring 31 is arranged in the spring-casing so as to extend about the journal or axle members 19 and 20 and has one 20 end portion connected to the magazine cylinder 24 by means of a nail or stud 32, the opposite end portion of the spring having a hook 33 which is inserted in an aperture 34 in the rim portion 28 of the spring-casing, 25 so that the spring shall act to turn the cylinder in one direction.

A novel hammer is provided which comprises a beam 35 that is pivotally mounted on a pivot 36 supported by the members 30 19 and 20, the beam being arranged between said members and having an upwardly extending arm 37 on one end thereof that has a hammer head 38 on its end, the opposite end of the beam having a 35 finger 39 thereon extending upwardly, the arm 37 and the finger 39 being arranged on opposite sides respectively of the magazine cylinder. Preferably the beam 35 has reinforcing plates 40 and 41 secured thereto 40 which conveniently add width to the end portion of the beam below the finger 39, which is desired. A strong spring 42 is arranged between the side bars 17 and 18 and is connected with the finger 39 and also with 45 an anchor-pin 43 connected to the side bars. The spring normally holds the finger 39 against a stop - pin 44 which is secured to the wings 15 and 16. An operating shaft 45 is rotatably mounted in the wings 15 and 16 50 and has a crank arm 46 thereon provided with a handle 47, and a suitable cam 48 is arranged between the wings and secured to the shaft 45, and is suitably shaped to constitute a rotary trigger to repeatedly tilt 55 the hammer in opposition to the spring 42 and permit the spring to operate the hammer, the cam being arranged to have contact with the bottom of the beam below the finger 39. In its most simple form the cam is designed to tilt and retract the hammer once on each revolution of the operating shaft 45.

An improved gun is provided which comprises a cylindrical main portion 49 and a barrel portion 50, preferably composed of a 65 single piece of wood and having a smooth

bore 51 extending therethrough, the main portion being seated upon the side bars 17 and 18 and secured thereto by means of a screw 52 arranged in a projecting portion of the gun stock 13. The main portion 49 has 70 a longitudinal recess 53 at one side of the bore to permit the projectiles to be carried transversely into the bore adjacent to the breech-end of the gun. The under side of the main portion 49 has a recess 54 therein 75 extending transversely which receives the peripheral portion of the magazine cylinder, said under side having also a longitudinal groove 55 extending to the bore 51 and from the breech-end of the gun to receive the hammer head 38 and adjacent portion of the arm 37. The arm 37 is of suitable length to carry the hammer head into the bore 51. The hammer head is of sufficient length to extend into one of the openings 26 or may be stopped against the cylinder 24 when none of the openings is fair with the bore 51, to hold the cylinder against rotation.

The magazine comprises also a stationary 90 guide casing which is associated with the magazine cylinder and comprises a circular metallic body portion 56 having lips 57 and 58 that are secured to the main portion 49 of the gun. A brace 59 is suitably secured 95 to the body portion 56 and also to the bottoms of the wings 15 and 16, which are suitably recessed to clear the front ends of the projectiles and receive one edge of the body portion 56 which has a stop-ring 60 extending inwardly to guide the nose ends of the projectiles, the opposite edge of the body portion 56 having an inward extending ring 61 to guide the rear end of the projectiles. The ring 61 has an opening 62 therein and 10 a pivot 63 in proximity to the opening which supports a shutter 64 adapted to close the opening. For the purpose of turning the magazine cylinder 24 a handle 65 is connected to the outer face thereof and in such 11 arrangement that it is carried into contact with the main portion 49 of the gun barrel when the last projectile chamber or opening 26 of the series is brought into alinement with the bore 51, to serve as a stop for 11 the cylinder when emptied.

The machine gun is supplied with projectiles 66, 66', each having the general shape of a real cartridge or loaded shell, one end thereof being rounded to represent the nose 12 portion, the opposite end being flat to be struck by the hammer head 38. The projectiles may be composed of various substances, preferably of wood.

In operation of the machine gun the cylinder 24 is turned by means of the handle 65 in the direction opposite to that exerted by the actuating spring 31 while filling the magazine with the projectiles, so that the last projectile placed in the magazine cylin- 13

der will be the first one to be carried into the gun barrel to be projected in the operation of "firing" the gun. To permit insertion of the projectiles the shutter 64 is first 5 opened to uncover the opening 62, and the cam 48 is set so as to hold the hammer in retracted position permitting rotation of the cylinder. When it is desired to hold the cylinder temporarily against rotation the 10 cam is turned backward until the hammer head 38 is spring-pressed into contact with the magazine cylinder. When each chamber or pocket 26 is brought to the opening 62 a projectile is readily inserted through 15 the opening and into the chamber. When each projectile is carried into the gun barrel by the rotating magazine cylinder the projectile prevents further movement of the cylinder. Having filled the magazine the 20 shutter 64 should be closed, the stationary portion of the magazine then preventing accidental dislodgment of the projectiles from the magazine. The machine gun is "fired" simply by the operation of the operating 25 shaft 45 in one direction so that the cam or rotary trigger 48 shall first retract the hammer and then permit the spring 42 to thrust the hammer forward so as to strike the projectile and suddenly force it out of the 30 magazine cylinder and the gun barrel, the hammer being quickly retracted so as to permit the actuating spring 31 to slightly turn the magazine cylinder and bring another projectile into the bore of the gun barrel, the firing operations being rapidly 35 repeated until all the projectiles have been ejected; but the "firing" may be stopped at any time if the operating shaft be stopped. After the hammer has struck and ejected 40 each projectile the finger 39 comes into contact with the stop-pin 44, and the beam 35 of the hammer may strike the hub of the cam 48 so, as to cause a noise in imitation of an explosion in the gun barrel.

45 Having thus described the invention, what is claimed as new is:—

1. A toy machine gun having a gun stock provided with a journal, a magazine cylinder rotatably mounted on the journal, a 50 hammer pivotally supported by the journal, and a trigger mounted in the gun stock to control the hammer.

2. A toy machine gun having a stationary magazine casing, a magazine cylinder rotatable in the magazine casing and adapted to coöperate therewith to carry and guide projectiles, and means for driving the projectiles out of the magazine cylinder.

3. A toy machine gun including a gun 60 barrel, a rotatable magazine cylinder having a handle to turn the cylinder in one direction, means for turning the cylinder in the opposite direction, a hammer provided with an actuating spring, and rotary means 65 for controlling the hammer.

4. A toy machine gun provided with a magazine comprising a rotary cylinder having transverse grooves in its periphery, and a stationary part comprising a circular guide extending opposite to the periphery 70 of the cylinder, and two guide rings on the two opposite edges respectively of the circular guide.

5. A toy machine gun having a hammer comprising a pivoted beam and a hammer 75 arm and a finger on opposite end portions respectively of one side thereof, the hammer arm having a projecting head on the side thereof that is presented toward the finger; an actuating spring connected to said finger, 80 and means for coöoperating with the spring to control the hammer.

6. A toy machine gun including a gun stock, a gun barrel on the stock, a cylinder rotatable on the stock and having openings 85 to receive projectiles, a hammer movably mounted in the stock to eject the projectiles or to engage and hold the cylinder, a spring for operating the hammer, and a cam in the gun stock and movably controllable to control the hammer.

7. A toy machine gun having a gun barrel with a bore therein, one side of the barrel having an opening therein extending to the bore to receive a projectile, the under side 95 of the barrel having a transverse recess to receive a device for carrying the projectile, and having also a longitudinal slot extending to the bore to receive a hammer for ejecting the projectile from the bore.

8. A toy machine gun including a gun stock, a gun barrel secured to the gun stock, a magazine cylinder rotatably mounted on the gun stock to carry projectiles successively into the gun barrel, a spring for rotating the magazine cylinder in one direction, a hammer pivoted in the gun stock for ejecting the projectiles from the gun barrel, an actuating spring for the hammer, and a trigger rotatably mounted in the gun stock 110 to control the spring.

9. In a toy machine gun, the combination with a gun barrel, of a gun stock supporting the barrel and having two journal members, a magazine cylinder rotatably mounted 115 on the journal members, and a hammer having its body portion arranged between the journal members and pivotally supported thereby.

10. In a toy machine gun, the combination with a gun stock, a magazine cylinder rotatably mounted on said stock, and a hammer movably mounted in said stock, of a gun barrel secured to the gun stock and having a transverse recess in its under side receiving a portion of the magazine cylinder and having also a slot in its under side to receive the hammer.

11. In a toy machine gun, the combination of a gun stock, a gun barrel, a maga- 130

- zine comprising a chambered cylinder rotatable on said stock and a guide casing stationarily secured to said stock, a spring for actuating said cylinder, a hammer mov-
5 ably mounted on said stock and adapted to stop said cylinder and adapted also to enter the chambers of the cylinder, means for actuating the hammer, and means for controlling the actuation of the hammer.
- 10 12. In a toy machine gun, the combination of a stock, a barrel mounted on the stock, a cylinder rotatable on the stock and having recesses in its periphery, the cylinder having also a handle thereon to be carried thereby to one side of the barrel to stop the cylinder, a spring for rotating the cylinder, a casing extending about the cylinder and secured to said stock and having an opening therein to which the recesses may
15 be separately brought by said cylinder, and a shutter movably connected to the casing to close said opening.
13. In a toy machine gun, the combination with a gun barrel, of a stock connected to the gun barrel and having a journal thereon, a magazine cylinder rotatable on the journal and having grooves transversely arranged in its periphery, a guide casing extending about said cylinder and secured to
20 a portion of said stock and also to said barrel, a spring-case secured to said journal, a spring connected to the magazine cylinder and the spring-case, a hammer pivotally connected with said journal, an actuating spring for the hammer, and a trigger to control the hammer.
- 30 14. In a toy machine gun, the combination with a gun barrel, of a stock having two side bars thereon connected to the gun bar-
35 rel, the stock having also two separate wings 40 thereon provided with journal members respectively, a magazine cylinder rotatably mounted on the journal members and having a handle thereon to rotate the cylinder in one direction, a casing secured to the journal members, a spring connected to said cylinder and said casing to rotate the cylinder in the opposite direction, a hammer having its main portion arranged between said journal members and pivotally supported thereby, a spring arranged between said side bars to operate the hammer, and a rotary trigger mounted between said wings to control said hammer.
15. In a toy machine gun, the combination of a gun stock having a hollow journal, a barrel secured to said stock, a magazine cylinder rotatably mounted on the hollow journal, a hammer having a main portion arranged in the hollow journal and pivotally supported thereby, the hammer having a hammer arm extending from said portion on one side of said cylinder and also a finger extending from said portion on the opposite side of the cylinder, a spring connected to said stock and also to said finger to actuate said hammer, an operating shaft mounted in said stock, and a trip cam secured to the operating shaft to engage and retract said hammer and permit actuation 55 60 65 70 of the hammer by said spring.

In testimony whereof, I affix my signature in presence of two witnesses.

WALTER O. McDANIEL.
